UNITED STATES PATENT OFFICE

152,430

DESIGN FOR A BICYCLE

Marcel Mennesson, Neuilly-sur-Seine, France, assignor to Societe D'Appareil De Controle & D'Equipment Des Moteurs (S. A. C. E. M.) S. A., Neuilly-sur-Seine, France, a society of France

Application May 10, 1946, Serial No. 129,587
In France June 15, 1943

Section 1, Public Law 690, August 8, 1946

Term of patent 14 years

(Cl. D90—8)

To all whom it may concern:

Be it known that I, Marcel Mennesson, a citizen of the Republic of France, residing at Neuilly-sur-Seine (Seine) France, have invented a new, original, and ornamental Design for a Bicycle, of which the following is a specification, reference being had to the accompanying drawings, forming part thereof.

Fig. 1 is a side view of a bicycle, showing my new design; and

Fig. 2 is a perspective view thereof.

I claim:

The ornamental design for a bicycle, as shown.
MARCEL MENNESSON.
